UNITED STATES PATENT OFFICE.

JONAS L. KNOLL, OF LEBANON, PENNSYLVANIA.

DESIGN FOR A BICYCLE-FRAME.

SPECIFICATION forming part of Design No. 34,903, dated August 6, 1901.

Application filed July 5, 1901. Serial No. 67,248. Term of patent 14 years.

To all whom it may concern:

Be it known that I, JONAS L. KNOLL, a citizen of the United States, residing at Lebanon, in the county of Lebanon and State of Pennsylvania, have invented and produced a new and original Design for a Bicycle-Frame; and I do hereby declare the following to be a full, clear, and exact description of the same, reference being had to the accompanying drawing, forming a part thereof.

The drawing represents my bicycle-frame in perspective.

The invention relates to what is known as a "lady's bicycle-frame."

The leading features of my design consist in the backbone A in the form of a flat spring-bar slightly arched, the front end of the backbone terminating in a seat-post B, also in the form of a flat spring-bar slightly inclined rearwardly, the rear end of the backbone be-

ing in the form of a forked member d, each branch of which is pivoted to the upper portion of a three-arm block K. The post B has its lower end secured to the shaft-hanger C, and the portion below the middle of its length is secured to the front reach D. The middle portion of the post B has secured to its rear a bow-shaped brace F, which is united to the upper branches of the blocks K by a looped tubing E, as shown. 25

Having fully described my invention, I claim—

The design for a bicycle-frame as herein shown and described.

In testimony whereof I affix my signature 35 in presence of two witnesses.

JONAS L. KNOLL.
